US0D1079630S

(12) **United States Design Patent** (10) **Patent No.:** **US D1,079,630 S**
(45) **Date of Patent:** **** Jun. 17, 2025**

(54) **WIRELESS SELFIE LIGHT POWER BANK**

(71) Applicant: **Shenzhen Shanmu New Energy Technology Co., Ltd.**, Guangdong (CN)

(72) Inventor: **Dingwu Yang**, Shanghai (CN)

(73) Assignee: **Shenzhen Shanmu New Energy Technology**, Shenzhen (CN)

(**) Term: **15 Years**

(21) Appl. No.: **29/988,989**

(22) Filed: **Feb. 8, 2025**

(30) **Foreign Application Priority Data**

Jan. 11, 2025 (CN) 202530018029.1

(51) **LOC (15) Cl.** **13-02**

(52) **U.S. Cl.**

USPC **D13/108**

(57) **CLAIM**

The ornamental design for a wireless selfie light power bank, as shown and described.

DESCRIPTION

FIG. 1 is a front and top perspective view of a wireless selfie light power bank showing my new design;

FIG. 2 is a rear and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the wireless selfie light power bank that form no part of the claimed design.

1 Claim, 8 Drawing Sheets
